CLAIM

The ornamental design for an industrial robot controller, as shown and described.

DESCRIPTION

FIG. 1 illustrates a front view of an industrial robot controller.

FIG. 2 illustrates a rear view of the industrial robot controller shown in FIG. 1.

FIG. 3 illustrates a left side view of the industrial robot controller shown in FIG. 1.

FIG. 4 illustrates a right side view of the industrial robot controller shown in FIG. 1.

FIG. 5 illustrates a top view of the industrial robot controller shown in FIG. 1.

FIG. 6 illustrates a bottom view of the industrial robot controller shown in FIG. 1.

FIG. 7 illustrates a bottom perspective view of the industrial robot controller shown in FIG. 1.

FIG. 8 illustrates a bottom perspective view of the industrial robot controller shown in FIG. 1; and,

FIG. 9 illustrates a front perspective view of the industrial robot controller shown in FIG. 1.
